FLAP

Edward Frank Zaparka, Baltimore, Md., assignor
to Zap Development Corporation, Baltimore,
Md., a corporation of Delaware

Application August 7, 1933, Serial No. 684,048
Renewed September 13, 1937

2 Claims. (Cl. 244—42)

My invention relates to a flap operating mechanism, and more particularly to an operating mechanism for extending and retracting flaps adapted to operate in an air stream through which an aerodynamic device is moved.

Particular embodiments are shown, but it is to be understood that I am not to be limited in the scope of my claims to any particular embodiment. In the drawings my flap is shown mounted near the trailing edge of a wing.

In my copending application Serial No. 657,133 I have explained the advantages of the type of wing flap whose trailing edge moves in a straight line directly below the trailing edge of the wing. Another way of stating this is to say that the movement of the trailing edge of the flap is such as to cause it in extended positions to lie within the locus of perpendiculars drawn to the datum lines of the wing sections and which pass through the trailing edge of the wing. Such a flap construction minimizes the shift in center of pressure on the wing upon movement of the flap into operative position, and at the same time increases the lift of the wing.

This application shows improvements on the type of flap shown in application 657,133. Such improvements comprise means for more accurately controlling the movement of the trailing edge of the flap. In the particular embodiments shown the trailing edge of the flap is designed to move in a straight line and downward directly below the trailing edge of the wing. The mechanism is so adjusted as to give a more accurate control in this movement of the trailing edge than has heretofore been possible with the mechanisms previously employed.

The inherent advantages of this close line approximation of the movement of the flap within the zone of theoretically greatest efficiency, produce desirable characteristics which are an improvement upon the flaps previously disclosed.

My mechanism can be so adjusted as to give the desired movement of the flap within quite small limits of tolerance; limits considerably smaller than heretofore possible with other mechanisms.

My flaps can be used in places other than on wings, such as on control surfaces, or in other positions on either heavier or lighter than air craft of different types.

Fig. 1 is a side elevation of an airplane showing my flap in operative position on a wing, the control mechanism being indicated somewhat schematically by dotted lines.

Fig. 2 is a detailed view of the operating mech-

anism for controlling the position of the wing flaps, the parts being broken away to save space.

Fig. 3 is a vertical section taken through the trailing edge of a wing, showing the flap pivoting mechanism, the extended position of the flap being shown in the dotted lines.

Fig. 4 is a top plan detailed view of the operating mechanism for moving the flaps into and out of their nested position at the rear of the wing.

Fig. 5 is a graph showing the geometric positions of the parts when extending the flap shown in Figs. 1 to 4 inclusive.

Fig. 6 is a vertical section taken through a wing showing another type of flap and operating mechanism.

Fig. 7 is a view taken along the lines 7—7 of Fig. 6 looking in the direction of the arrows.

Fig. 8 is a perspective view showing the housing for the link support for the flap.

Fig. 9 is a graph depicting the geometry of 20 operation of the flap shown in Figs. 6 to 8 inclusive.

Referring to the drawings I have shown an airplane having a fuselage 1, a motor 2 and a propeller 3. The empennage surfaces I have indicated generally by the numeral 4, which comprise the usual stabilizer, elevator and rudder surfaces. The plane is of the monoplane type and is provided with wings 5, each of which is provided with a wing flap 6. Mounted over each of the wings are ailerons 7 on supports 8. The ailerons are provided with aileron horns 9 to which operating rods 10 are attached. The mechanism for operating the ailerons 7 mounted over the rear of the wings has been covered in other copending applications, and it is not thought necessary to describe their functions and construction in detail.

The flaps 6 are of the type which are so mounted that their trailing edges shall lie within the locus of perpendiculars drawn to the datum line of the wing sections and which pass through the trailing edges of the wings.

The flaps 6 are adapted to have their trailing edges travel in substantially a straight line in being extended or retracted. Heretofore, for instance in my application Serial No. 657,133, I have indicated that this movement of the trailing edge of the flaps was desirable. The mechanism which I here show, however, gives a more accurate control over such movement, and the positions of the flap during its movements under the control of the operating mechanism more closely approximate the theoretically perfect

than is possible with any of the constructions shown in my other copending applications.

The flaps 6 are provided with a lower flap member 11 which may be of sheet metal over which fits a member 12 having corrugations which run in the opposite direction from the corrugations 13 on the member 11. This construction gives great strength and rigidity with little weight.

- 10 Attached to the upper surface 12 of the flap 6 are angular support pieces 14 which may be riveted or otherwise suitably attached to the upper surface. These angular support pieces are provided with upstanding sides 15 which are 15 at one end extended into an upstanding member 16 which carries a rod 17 having thereon pivot pieces or rollers 18 carried at its ends. The pivot pieces or rollers 18 are adapted to fit within stop or guideways 19 formed in supports 20. 20 The supports 20 are of angular configuration, there being a pair of supports 20 at each station where a flap operating mechanism is located. There are generally a series of stations along each wing. In Figure 4 I have shown two stations, though there may be more, or in some instances one station may suffice.

The supports 20 are flanged at their outer edges for greater strength and rigidity, and also flanged in proximity to the slots 19. The supports 20 are fastened by bolts 21 to a rear wing spar 22 of each wing. Attached to the supports 20 at their rear edges are support members 23 between which is pivoted on a pivot 24 a link 25. There may be provided washers 26 to permit 35 the link 25 to rotate freely. The other end of each of the links 25 is pivoted at 27 to the flap 6. A projection 28 is formed on the lower surface of the flap to provide free movement of the link 25 on its pivot 27 without binding the flap in its 40 movement.

The length of the link 25 and the convolution of the slot 19 is such that upon movement of the rollers 18 rearwardly the flap is opened, as indicated in dotted lines in Fig. 3, to cause the 45 rear or trailing edge of the flap to fall, in all of its extended positions, within very close ranges of tolerance within the locus of perpendiculars to the datum lines of the wing sections, which pass through the trailing edges of the wing.

50 It will be noted that the slot 19 is not shown as proceeding in a straight line, but is provided with convolutions as shown in Fig. 3, and the convolutions are such as to accurately determine that the trailing edge of the flap shall lie within the 55 defined locus which may be indicated as the optimum movement of my flap.

In order to cause the rollers 18 to be either pushed to the rear or pulled to the front to open and close the flap, I have provided controlling 60 linkages which I will now describe. Passing through the rods 17 are pivots 29 which pass through U-shaped ends 31 of rods 32. The rods 32 are pivoted at 33 to one end of an arm 34 of a bell crank lever 35 which is pivoted at 36 on a triangular support construction 37.

The triangular support construction 37 is provided with cut-out portions 38 to lighten the construction. The supports 37 are of box-like construction and provided with apertures, as indicated at 39 and 40, to permit the movement of the bell crank 35 to operate the flaps. The bell crank 35 has another arm 41 which has a U-shaped head 42 through which a pivot pin 43 passes. 75 The pivot pin 43 is located on an operating head

44 which is screw-threaded to a shaft 45. There are two shafts 45, one for each wing.

The operating head 44 also carries one end of an operating link 46 which is adapted to operate another bell crank 35 at a remote station. The 5 number of bell cranks and the number of linkages to operate them can be multiplied beyond two, as above set forth.

Each shaft 45 is connected through a gimbal joint 47 to another shaft 48, on which is mounted a beveled pinion 49. The beveled pinion 49 meshes with a beveled pinion 51 mounted on a shaft 52. The shaft 52, at its other end, carries a beveled pinion 53 which meshes with a beveled pinion 54 mounted on a shaft 55. A hand crank 56 is adapted to rotate the shaft 55, and through the shafts and pinions indicated the shaft 48 may be rotated in either direction of rotation desired by the pilot.

The rotation of the shaft 48 through the gimbal joint 47 rotates the shaft 45 to operate the flaps. The rotation of the shaft 45 moves the operating head 44 in either direction, depending upon the direction of rotation of the shaft 45 and this, through the bell crank linkages, pulls or 25 pushes on rods 32 to raise or lower the flaps.

Similar or equivalent mechanism can be used to operate flaps for control surfaces, or even to operate aileron flaps, or flaps in any position where they may be employed in either lighter or 30 heavier than air craft.

The geometry of the moving parts is graphically illustrated in Fig. 5, where the movement of the pivot pieces along the tracks 19 is indicated. The movement of the pivots 27 is indicated at 35 the point marked "Link movement". The movement of the trailing edge of the flap is shown.

I have indicated in Figs. 6, 7 and 8 another form of flap operating mechanism in which the trailing edge of the flap very closely approximates the theoretically desirable movement above 40 set forth. In this case the shaft 45 is provided with a series of beveled pinions 57 which engage with beveled pinions 58 carried on operating rods 59 that are journaled in journals 61 which are 45 carried by the rear wing spar 22. There is an operating rod located at each flap operating station in each wing. The construction at the rear of the wing comprises bracing members 63 which are attached, through the bolts 21, to the rear wing spar 22. The operating rod 59 is journaled at 64 at the rear of the bracing members 63.

The operating rods 59 are provided with screw-threaded sections 65 on which fit operating heads 66 which may be keyed, as indicated at 67, to keyways 68 carried by the support members 63. The construction of the flaps 6 is almost identical with that previously disclosed. The upstanding members 16 are pivoted at 69 to the operating heads 66. Pivoted at the pivot points 27 on the flaps 6 are links 71, which may have bent portions 72 to permit free movement of the flap and the links. The links are further bent, as indicated at 73, and are pivoted at 74 to supports 75 which may be extensions of the support members 63.

Stream-lined housings 76 are formed at each station, as indicated in the drawings, to streamline the support for the links 71. It will be noted that by the use of such stream-lined housing, the links 71 may be pivoted substantially 70 in line with the trailing edge of the wings 5. The pitch of the screw-threaded portions 65, the length of the links 71 and the length of the flap, and other factors, are such as to insure that the trailing edge of the flaps shall lie within very 75

close approximation to the theoretically desirable position, in which the trailing edges of the flaps lie directly below the trailing edges of the wings, and, substantially in the locus of perpendiculars to the wing chords which pass through the trailing edges of the wings.

In Fig. 9 the geometry of movement of the parts of the type of flap depicted in Figs. 6, 7 and 8 is shown. It will be seen that the trailing edge of the flap can be held within a very close approximation to the theoretically desired movement.

I claim:

1. A wing flap mechanism comprising a wing, a rear spar for the wing, a flap pivotally supported below the wing, flap operating mechanism comprising a member mounted on the rear spar of the wing and extending rearwardly therefrom within the wing and formed with a cam slot, a support attached to the flap, a pivot piece supported by said support, a link pivoted below the upper surface of the wing at one end and to the flap at the other end, said pivot piece on the upstanding member being adapted to lie within

said cam slot whereby the trailing edge of the flap shall move within small limits of tolerance within the locus of lines drawn perpendicular to the datum lines of the wing sections and which pass through the trailing edge of the wing.

2. A flap mechanism comprising a wing, a flap pivotally supported below the wing, flap operating mechanism all without the airstream and comprising a support secured to the wing structure and extending in a fore and aft direction 10 within the wing and having a guiding cam slot formed therein, a link pivoted at one end to said support and at the other end to said flap at a point spaced rearwardly from the nose of the flap, a pivot piece secured to the flap adjacent the 15 nose thereof and cooperating with said guiding cam slot, the convolutions of said cam slot being such as to insure that the trailing edge of the flap shall move within small limits of tolerance within the locus of lines drawn perpendicular to 20 the datum lines of the wing sections and which pass through the trailing edge of the wing.

EDWARD FRANK ZAPARKA.
